UNITED STATES PATENT OFFICE.

JOHN J. GRODEN, OF PHILADELPHIA, PENNSYLVANIA.

WASHING MACHINE.

Application filed July 22, 1922. Serial No. 576,827.

To all whom it may concern:

Be it known that I, JOHN J. GRODEN, a citizen of United States, residing at Philadelphia, in the county of Philadelphia and State of Pennsylvania, have invented new and useful Improvements in Washing Machines, of which the following is a specification.

This invention relates to laundry apparatus, particularly to washing machines, and has for its object the provision of a novel electric motor driven combined rotary and oscillatory washer and wringer.

An important object is the provision of a machine of this character in which the moving parts are all enclosed within a cabinet, the wringer structure being also capable of being swung into position within the cabinet so as to prevent children or others from starting the mechanism and catching their hands in the wringer structure.

Still another object is the provision of a changeable drive whereby a rotary cylinder or oscillatory tub may be used by making a simple adjustment.

A further object is the provision of drive means provided with a control whereby the tub may be oscillated or the cylinder rotated at different speeds depending upon the nature of the articles being washed.

A further object is the provision of a washing machine in which the tub or cylinder, as the case may be will be lifted up by a suitable control device to permit draining and to bring the tub or cylinder close to the wringer to make it unnecessary for the operator to stoop over to gain access to the clothes and thus run the danger of catching the hair or clothing in the wringer.

Yet another object is the provision of a device of this character in which the wringer is provided with control means whereby it may be held inoperative or be driven in either direction, the wringer structure being, furthermore, capable of rotatable swinging movement to be disposed at any desired location.

A still further object is the provision of novel means engageable with the floor for lifting one end sufficiently that the casters will be out of engagement with the floor or other surface in order that the device may be prevented from rolling accidentally.

An additional object is the provision of

a machine of this character which will be simple and inexpensive in manufacture, easy to control and adjust, positive in action, efficient and durable in service and a general improvement in the art.

With the above and other objects and advantages in view the invention consists in the details of construction to be hereinafter more fully described and claimed and illustrated in the accompanying drawings, in which:

Figure 1 is a perspective view of the complete device,

Figure 2 is a plan view with a portion of the cylinder broken away,

Figure 3 is a vertical section taken through the cabinet and showing a side elevation of the drive mechanism,

Figure 4 is a vertical section taken from the opposite side to Figure 3 and showing the drive mechanism,

Figure 5 is a horizontal section through the drive mechanism taken on the line 5—5 of Figure 4,

Figure 6 is a detail sectional view of the releasing means for the cylinder trunnions,

Figure 7 is a detail sectional view of the means for raising the casters off of the floor.

Figure 8 is a detail sectional view showing the means for raising the rotary cylinder or oscillatory tub,

Figure 9 is a detail sectional view through a portion of the wringer drive mechanism, and

Figure 10 is a detail sectional view.

Referring more particularly to the drawings I have shown my device as comprising a rectangular frame constructed preferably of angle iron and including legs 15 and upper and lower cross bars 16. The legs and bars have secured thereto metal sheathing 17 which may be held in place by flush rivets, by spot welding or the like. This structure defines a rectangular casing open at the top and bottom. The open top is reinforced internally by an angle iron member 18 which provides securing means for some of the elements of the device. One side of the casing is provided with a hinged door 19 having a handle 20 and which may be opened to give access to the mechanism to be described.

The top of the case or cabinet is designed to be closed by a removable covering 21

which will operate to prevent dust and dirt from settling on the device when it is not in use but of course this cover must be removed when the device is being used.

5 Located within the casing and supported from the angle iron 18 is a tub 22 which has its bottom semicylindrical in shape and this tub is provided at its lowermost point with a suitable drain cock 23 by means of 10 which the water may be drained out into a receptacle or through a pipe 24. Secured within the device are upwardly extending guides 25 within which are slidable, as well as rotatable, trunnions 26 and 27 carried by 15 the ends of a rotary cylinder 28. This cylinder is perforated throughout its periphery as shown at 29 and has a portion thereof 30 removable whereby to give access to the interior for placing clothes therein or 20 removing them therefrom.

The drive mechanism is constructed as follows: Mounted upon a suitable support 31 at the bottom of the device is a suitable electric motor 32 having its shaft 33 carrying a worm 34 which meshes with a worm wheel 35 on the lower end of a vertical shaft 36 which has its upper end portion journaled in a bearing 37 located at one upper corner of the cabinet and which has its intermediate portion journaled through bearings 38 on a frame 39 which is mounted transversely of the main frame of the device. Within the frame 39 the shaft 36 carries a worm 40 which meshes with a 35 worm wheel 41 on a short shaft 42 which carries large and small gears 43 and 44 respectively. Journaled at a point spaced from the shaft 42 is a similar shaft 45 upon which are rotatable gears 46 and 47 40 meshing always with the gears 43 and 44 respectively. The confronting faces of these gears carry clutch faces 48 and 49 respectively. Splined upon the central portion of the shaft 45 is a grooved collar 50 45 provided with clutch faces 51 and 52 adapted to engage with either of the clutch faces 48 and 49 respectively. I provide an arm 53 carried by a shaft 54 and terminating in a fork 55 which engages within the 50 grooved collar 50 for the purpose of shifting the collar lengthwise to bring the clutch face 51 into engagement with the clutch member 48 for operating the machine at high gear, or for bringing the clutch face 55 52 into engagement with the clutch member 49 for the purpose of operating the machine at low speed. The control shaft 54 is provided with a suitable handle 56 by means of which the gear shifting may be 60 accomplished. One projecting end of the shaft 45 carries a crank arm 57, which is formed with a slot 58 for a purpose to be described.

The trunnion 27 of the rotary cylinder 65 is formed with an angular socket 59. Slid-

able and rotatable through the frame 39 in alignment with the longitudinal axis of the cylinder is a shaft 60 carrying an angular extension 61 normally engaging within the socket 59. Splined upon this shaft 60 and 70 prevented from shifting movement by the sides of the frame 39 is a gear 62 with which meshes a segmental gear 63 carried by a shaft 64 upon which is secured a crank arm 65 on the free end of which is pivoted, 75 at 66, a block 67 through which passes a rod 68 carried by a pitman 69 which carries a bolt 70 adjustably mounted at a selected point within the slot 58 of the arm 57. Located at opposite sides of the block 75 80 are shock absorber springs 71 held in place as shown and which are for the purpose of cushioning the shock when the pitman 69 swings the crank arm 65 back and forth so as to avoid damage to the mechanism.

The shaft 60 projects beyond the frame 39 and carries a grooved collar 72 engaged by a fork 73 on one end of a lever 74 which is pivoted intermediate its ends as shown at 75. Slidable through one side of the cabinet, above one corner of the door 19 is a control button or plunger 76 which is connected with the upper end of the lever 74 for the purpose of rocking the same to withdraw the shaft extension 61 from the socket 59 so that the cylinder may be raised when desired by the means to be described.

Located within the casing at opposite ends of the cylinder are levers 77 terminating in handles 78 and pivoted as at 79. These levers are formed with cams 80 which engage the trunnions 26 and 27 for moving the cylinder upwardly along the guides 25 subsequent to actuation of the plunger 76 to effect withdrawal of the shaft extension 61 from the socket 59.

The wringer mechanism is also power driven from the same motor 32. This wringer mechanism comprises a base member 81 rotatably mounted at the top of the cabinet and further includes a gear box 82 and an upstanding frame 83 which carries the wringer rollers 84. The usual guide plates 85 are associated with this roller frame and I further provide a tension device 86 for loosening the tension on the rollers in case such is excessive or too great to permit a certain individual article to pass between the rollers. The rollers are equipped with the usual gears which intermesh.

The upper end of the power shaft 36 after passing through the bearing 37 at the top of the cabinet extends into the gear box 82 and carries a beveled gear 87. The drive shaft 88 of the wringer mechanism carries a sleeve 89 splined thereon and carrying two opposed beveled gears 90 and 91 selectively engageable with the gear 87. The

sleeve 89 is formed with a peripheral groove 92 within which engages a fork 93 carried by a shaft 94 having a control handle 95. By disposing this handle 95 at its intermediate position both gears 90 and 91 will be out of mesh with the gear 87 and by shifting this lever 95 in one direction or the other either of the gears 90 or 91 may be meshed with the gear 87 for driving the 10 wringer rollers in either direction.

The rotatable adjustable mounting of the wringer consists of a depending sleeve or hub 96 which is rotatable within the bearing 87 and which is engaged by a spring 15 pressed plunger 97 which extends outside of the casing or cabinet and which is for the purpose of frictionally holding the entire wringer structure in a selected rotatably adjusted position.

20 A very important feature is the means by which the wringer structure is permitted to be swung down so as to be enclosed by the cover 21 when the latter is placed in position. To accomplish this the frame 83 of the 25 wringer is pivoted upon the shaft 88 and carries a spring pressed plunger or locking pin 98 which engages within a suitable notch 99 in the top of the gear box 82 for holding the wringer frame in normal or up- 30 right position. By withdrawing the pin 98 from the notch 99 the wringer frame may be rotated upon the shaft 88 and be disposed in a horizontal position as shown by full lines in Figure 3.

35 It is to be observed that the supporting legs 15 of the casing are equipped with casters 100 which will facilitate moving the device from place to place. However, it is advisable to provide means for preventing 40 this rolling action and holding the device stationary. In accomplishing this I provide adjacent the front legs of the device suitable frames 101 within which are vertically slidably posts 102 which have their 45 lower ends carrying bearing feet 103 engageable with the floor. These posts are normally urged downwardly by coil springs 104 which encircle their upper ends and which bear against the underside of the 50 tops of the frames 101 and against collars 105 on the posts. The means for moving the posts upwardly consists of a cam 106 pivoted on each post and having a projecting handle 107 operating through a slot 108 55 in the frame. Each frame further carries a bracket arm 109 engaged by the cam head so that when the cam is swung down the engagement of the head thereof with the bracket 109 will cause the post 102 to 60 be forced up against the resistance of the spring 104. It is of course conceivable that this mechanism might be duplicated at each leg of the device though it is believed that two of such units will be entirely sufficient 65 to effect the purpose.

Instead of providing the device with the tub 22 and perforated cylinder, I may omit the tub and use an oscillatory tub such as that shown in Figure 8. This type of tub 110 is not purely cylindrical and is im- 70 perforate but is provided with a removable cover member 111 which may be removed when placing clothes therein or removing them therefrom.

In the operation it will be seen that when the motor 32 is in motion the shaft 36 will be consequently driven and will operate the wringer whenever the lever 95 is thrown to engage either of the gears 90 or 91 with the gear 87. If desired the wringer may be left 80 inactive by moving the lever 95 to neutral position. The rotation of the shaft 36 of course is imparted to the shaft 42 and through either of the gears 43 and 46 or 44 and 47 to the shaft 45 depending upon which 85 way the lever 56 is shifted. If the lever 56 is in intermediate position with the sliding clutch sleeve 50 out of engagement with both of the clutch elements 48 and 49 the motor will run idly and the shaft 45 will 90 not be driven. When, however, the shaft 45 is driven at the selected speed depending upon which gears are meshed, the rotation of the arm 57 will cause longitudinal movement of the pitman 69 and swinging of the arm 65 95 which will result in back and forth movement of the segmental gear 63. When the gear 63 moves, its engagement with the pinion 62 will cause rotation of the shaft 60, the angular extension 61 of which fits within 100 the socket 59. By this means it will be seen that the cylinder 28 or the tub 110 which ever is used, will be given rotary movement in one direction and then in the other which will result in thorough agitation of the clothes and water. In case the stationary tub 22 and perforated cylinder 28 are used it is obvious that the water within the tub 22 will pass through the perforations 29 into the cylinder and thoroughly act upon whatever clothes may be therein. In case the tub 110 is used the water is contained therein together with the clothes and the effective action will be the same in either instance.

115 After the clothes have been washed sufficiently and it is desired to remove them, the operator presses the plunger 76 to withdraw the shaft extension 61 from the socket 59 and then swings the lever 78 whereupon the cams 80 thereof riding under the trunnions 26 and 27 of the cylinder or the tub as the case may be will cause the cylinder or the tub to be moved upwardly along the guides 25 so that draining may be effected. The cylinder will then be in convenient position so that the clothes may be removed therefrom in a safe manner and with very little effort, the proximity of the tub or cylinder to the wringer facilitating the running of the clothes through the wringer 120 125 130

mechanism. The various safety features have been mentioned during the course of the general description and it is believed that a sufficient explanation thereof has been given without it being necessary to repeat.

From the foregoing description and a study of the drawings it will be apparent that I have thus provided a simply constructed washing machine and wringer which will be power driven and which is provided with every conceivable speed control, safety device and other advantageous features so as to produce in one machine all the advantages which may be possible to incorporate to insure efficiency and ease of operation together with maximum strength and durability.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I claim:

1. In a washing machine, a casing, guides mounted at opposite sides thereof, an oscillatory clothes container having trunnions slidably and rockably mounted within said guides, means detachably engaging one trunnion for oscillating the oscillatory container,

and means for raising the oscillatory container along said guides, said means consisting of levers pivoted within the casing and having cam portions engaging said trunnions.

2. In a washing machine, a casing, guides mounted at the opposite sides thereof, an oscillatory clothes container, trunnions on said container and slidably and rockably mounted in said guides, a substantially L-shaped lever pivotally mounted within said casing and having a cam portion engaging one of said trunnions for raising the clothes container upon movement of the lever in one direction.

3. In a washing machine, a casing, guides mounted at the opposite sides thereof, an oscillatory clothes container, trunnions on said container and slidably and rockably mounted in said guides, a substantially L-shaped lever pivotally mounted within said casing and having a cam portion engaging one of said trunnions for raising the clothes container upon movement of the lever in one direction, said substantially L-shaped lever being provided with a recess at the terminus of said cam for receiving the trunnions to hold the container in raised position.

In testimony whereof I affix my signature.

JOHN J. GRODEN.
